HAIR WAVING APPLIANCE

Eula M. Meyer and Edward C. Duncan,
Kansas City, Mo.

Application June 10, 1935, Serial No. 25,710

9 Claims. (Cl. 132—38)

Our invention relates to improvements in hair waving appliances. It relates particularly to a type in which flexible rod like toothed members are formed into U shape and are made to engage 5 the hair one above the other, and are moved endwise to form the hair into waves, the forward end portions of the hair engaging members being engaged and held by a front member which is attached to the head and is applied to 10 the upper and side portions of the face.

One of the objects of our invention is to provide novel means for engaging the hair engaging member with the front member, which places the hair engaging members at the outer side of 15 the front member, whereby they may be affixed to or detached from the front member without disturbing the latter or each other.

Another object of our invention is the provision of novel means by which when the hair 20 engaging members are adjusted endwise a lifting movement will be imparted to them causing the hair treated to simulate "finger" waves.

A further object of our invention is the provision of novel means for adapting the appliance 25 for use in making waves with the hair parted at either side or in the middle of the head.

Our invention provides further a novel hair 30 engaging member which will not hurt the head and will make rounded waves and not angular ones.

Our invention provides further novel means for releasably fastening the front member to the 35 head.

Another object of our invention is the provision of novel means for engaging and curling 40 the hair at the lower portion of the head and for attaching the curling means to the front member to retain the hair in the curled condition.

Still another object of our invention is the provision of a novel hair waving appliance, which is simple, cheap, durable, not likely to get out of order, which is easy to operate, which may be used without assistance by a person to wave 45 her hair, which may be employed to make a variety of wave formations, which is comfortable to use, and which is efficient in operation.

The novel features of our invention are hereinafter fully described and claimed.

In the accompanying drawing, which illustrates 50 the preferred embodiment of our invention,

Fig. 1 is a side elevation of our improved appliance shown in operative position upon the head.

Fig. 2 is reduced top view of the appliance, with the hair curling member omitted.

Fig. 3 is an enlarged stretchout view, partly broken away, of the front and top members.

Fig. 4 is an enlarged cross section on the plane

of the line 4—4 of Fig. 5 of one of the hair engaging members.

Fig. 5 is a section on the line 5—5 of Fig. 4.

Fig. 6 is an enlarged section on the line 6—6 of Fig. 1.

Fig. 7 is an enlarged plan view of intersecting 5 portions of the front and top members.

Fig. 8 is an enlarged section on the line 8—8 of Fig. 7.

Fig. 9 is a view of a portion of the hair curling 10 member, partly broken away, looking at one side thereof.

Fig. 10 is a view similar to Fig. 9, looking at another side of the hair curling member.

Similar characters of reference designate simi- 15 lar parts in the different views.

1 designates the front member, which may be of any suitable flexible material, such as a strip of sheet metal, as aluminum, brass or steel or a strip of celluloid, leather or soft rubber, and 20 which is adapted to be formed into horseshoe or other shape which will adapt it to fit different faces, and which is provided with two resilient metal bows 2 adapted to respectively have holding engagement with the ears, after the manner of spectacle bows, as shown in Fig. 1.

The front member 1 is adapted to be fitted against the upper and side portions of the face, and it has respectively attached to its end portions two strings 3 adapted to be passed under 25 the chin and tied together, as shown in Fig. 1.

4 designates a top member, which is in the form of a flat strip, which may be composed of material of the kind of which the front member 1 is composed, whereby the member may be formed into the shape desired. Its front end 30 is releasably fastened to the upper middle portion of the front member 1 from which it extends rearwardly so as to be adapted to be disposed over the top and back of the head, as 35 shown in Fig. 1.

The top member 4 is provided with a longitudinal row of slots 5, which are oblique to the length of the member, adjacent slots being inclined in opposite directions, as shown in Fig. 3.

The top member 4 is provided with means of attachment to the front member 1, that will permit of its being fastened thereto with its sides reversed, from the position shown in Fig. 3, 45 for the purpose hereinafter explained.

For engaging the hair to effect the waving thereof, there are provided a plurality of hair engaging members, which are alike and each of which comprises a cylindrical rod like body 6, of flexible, though relatively solid material, preferably leather, but which may be vulcanized 50 fibre, rubber or similar material.

Each body 6 is provided on one side with a longitudinal row of hair engaging teeth, each of which consists, preferably, of a staple 7 the arms 55

of which are extended into the body 6, and which are disposed in a plane transverse to the length of the body 6. The rounded end portion of the staple 1 projects approximately one eighth or three sixteenths of an inch from the body, and the staples may be disposed substantially that distance apart.

The bodies 6 are adapted to be formed into a substantial U shape, as shown, and are adapted to be disposed one above the other substantially parallel with each other, as shown in Figs. 1 and 2.

Each body 6 has inserted in its middle portion approximately diametrically opposite the side having the teeth 7, the stem of a T shaped guiding device 8 the projecting portion of which is insertable through either of the slots 5 in which the stem is slideable, and the transverse portion of which rides on the outer side of the top member 4 and is disposed transversely across the slot to support the rear portion of the body 6 when the latter is in the operative position shown in Figs. 1 and 2.

When the body 6 is formed into U shape and the arms thereof are forwardly extended with the teeth 7 engaging the hair, the end portions of the body extend across the outer side of the front member 1, as shown in Figs. 1 and 2.

For releasably fastening the end portions of the hair engaging members to the front member 1, the latter has mounted upon it in a longitudinal row of fastening devices, each of which comprises a U shaped spring clip 9 the middle portion of which is pivotally attached to the front member 1 by a tubular eyelet 10, the end portions of which are provided respectively with peripheral annular flanges 11 respectively engaging the inner and outer sides of the front member 1.

The spring clip 9 is disposed at the outer side of the front member 1, and its arms are extending toward each other so as to embrace and hold the body 6 which is inserted laterally into the clip, the extreme ends of the arms of which are turned outwardly to enable the ready insertion between them of the body 6. When so inserted, one of the teeth 7 extends into the eyelet 10 which holds the body 6 thereby from endwise movement.

In the application of the appliance to the head, the front member 1 is first made to engage the upper portion of the forehead, the temples and the side portions of the face just in front of the hair, as shown in Fig. 1. The bows 2 are engaged with the ears respectively and the strings 3 are tied together under the chin, the top member 4 being extended rearwardly over the top and back of the head.

The hair engaging member, which is to be the uppermost one, is then bent into U shape and has its T shaped guiding member 8 inserted from the under side of the top member 4 through one of the upper slots 5, with the stem of the guiding member 8 disposed in the lowermost end of the slot. The teeth 7 of the hair engaging member are then inserted into the hair, and the body 6 thereof is moved endwise in a direction which will cause the stem of the guiding member 8 to move upwardly to the upper end of the slot 5, after which the end portions of the body 6 are respectively laterally inserted into engagement with the spring clips 9 which are uppermost and are at opposite sides respectively of the top member 4, one tooth 7 of each inserted end portion entering the adjacent eyelet 10, whereby the body 6 is held from endwise movement, and the clips 9

retain the body 6 releasably held by the front member 1 in its wave forming position.

Another hair engaging member then has its guiding member 8 similarly engaged with the top member 4 by insertion outwardly through the slot 5 next below, and with its stem in the lower end of such slot. The teeth 7 of the member are then engaged with the hair, and the body is moved endwise in a direction opposite that in which the first body was moved, thereby causing the stem of the guiding member to move upwardly to the upper end of the slot 5, and moving with it the body 6, whereby the hair between the two members 6 is formed into a "finger" wave, the end portions of the second body 6 being respectively engaged with the two spring clips 9 next adjacent the ones which are engaged with the first body 6.

The succeeding hair engaging members are similarly applied, moved endwise in the hair, and fastened to the front member 1 by other clips thereon, in the manner already described with reference to the first two hair engaging members.

By reason of the opposite inclination of the slots 5, and the adjustment of the T shaped guiding members 8 therein, and the endwise movement in opposite directions of adjacent hair engaging members, as described, the hair is formed into a succession of finger waves one above the other extending around the head.

It will be understood that before so manipulating the hair, it is first treated in the usual manner with a suitable wave fixing material commonly employed for this purpose.

After the hair has been formed into waves, as has been described, the loose hair below the lowermost wave is curled in the way now to be described.

A cylindrical flexible rod like member 12 similar to one of the bodies 6, and composed of similar material, is provided with suitable means for clamping the hair to be curled to the member 12. In the form of such clamping means shown in Figs. 1, 9 and 10, a spring wire 13 of U shape is mounted on the member 12.

The transverse portion of the spring wire 13 is extended through the member 12, and the arms of the U shaped wire are respectively provided with U shaped end portions 14, oppositely disposed which are adapted to be releasably engaged with the member 12, as shown in Figs. 9 and 10.

The wire 13 is first disposed as shown in dotted lines in Fig. 10, in which the U shaped portions 14 thereof are disengaged from the member 12. The hair to be curled is then disposed between the arms of the wire 13 and the member 12, after which the U shaped portions 14 are lockingly engaged with member 12, as shown in Fig. 9 and in solid lines in Fig. 10. The member 12 is then axially revolved, thereby winding the hair upon the member 12, as shown in Fig. 1, and the end portions of the member 12 are then laterally inserted into holding engagement with two spring clips 9 on the front member 1 respectively near the lower ends thereof, as shown in Fig. 1.

After the curl has set, the end portions 14 of the wire 13 are disengaged from the member 12, and the member 12 and wire 13 are withdrawn from the curl which has been formed.

The top member 4, as has been stated is attached to the front member 1 so as to be reversed upside down from what is shown in Figs. 2 and 3, to enable the device to be adapted for wave making with the part of the hair at the

right or left of the head. For effecting this transposition, any suitable fastening means may be employed for connecting the top member to the front member. In the form shown, the 5 front member 1 has fastened in it two studs 15 with resilient expandable and compressible heads 16 adapted to respectively receive and have holding engagement with two eyelets 17 mounted in and extending through the member 4, Figs. 2, 3, 10 7 and 8.

By unsnapping the top member 4 from the front member 1, the top member may be reversed side for side and resnapped into holding engagement with the front member 1. This 15 change in position, will change the direction of formation of the waves, as effected by the same hair engaging members, by reversing the direction in which the latter are endwise adjusted in the slots 5.

20 Modifications of our invention, within the scope of the appended claims, may be made without departing from its spirit.

What we claim is:—

1. In a hair waving appliance, a front member 25 adapted to be applied to the upper and side portions of the face, a top member fastened to said front member and extending rearwardly over the head, a flexible hair engaging member adapted to be formed into U shape and to be adjusted 30 endwise in the hair and to have its end portions extended across said front member and having means at its middle portion engaging slidably said top member by which, when said hair engaging member is adjusted endwise its middle 35 portion will thereby be moved transversely to its length and lengthwise of said top member, and means for releasably fastening said end portions to said front member.

2. In a hair waving appliance, a front member 40 adapted to be applied to the upper and side portions of the face, a top member fastened to said front member and extending rearwardly over the head and having guiding means inclined to its length, a flexible hair engaging member adapted 45 to be formed into U shape and to be adjusted endwise in the hair and to have its end portions extended across said front member and having means slidably engaging said guiding means, by which, when said hair engaging member is endwise 50 adjusted, its middle portion will thereby be moved transversely to its length and lengthwise of said top member, and means for releasably fastening said end portions to said front member.

3. In a hair waving appliance, a front member 55 adapted to be applied to the upper and side portions of the face, a top member fastened to said front member and extending rearwardly over the head and having a slot inclined to its length, a flexible hair engaging member adapted to be 60 formed into a U shape and to be adjusted endwise in the hair and to have its end portions extended across said front member and having means extending through and guided in said slot by which, when said hair engaging member 65 is adjusted endwise, the middle portion thereof will thereby be moved transversely to its length and lengthwise of said top member, and means for releasably fastening said end portions to said front member.

70 4. In a hair waving appliance, a front member adapted to be applied to the upper and side portions of the face, a top member fastened to said front member and extending rearwardly over the head and having a longitudinal row of 75 slots adjacent ones of which are inclined to each

other in opposite directions, a plurality of flexible hair engaging members disposed one above the other and each being formed into U shape and adjustable endwise in the hair independently of the others and having its forward end portions extending across said front member, said hair engaging members having guiding means respectively in and guided by said slots, and means for releasably fastening the end portions of said hair engaging members to said front member. 10

5 5. In a hair waving appliance, a front member adapted to be applied to the upper and side portions of the face and having means for being fastened to the head, and a top member fastened to said front member and adapted to be extended 15 rearwardly over the head and having a longitudinal row of slots which are oblique to the length of said top member, adjacent ones of said slots inclining in opposite directions.

6. In a hair waving appliance, a front member 20 adapted to be applied to the upper and side portions of the face and having means for being fastened to the head, and a top member attached releasably and reversibly at one end to said front member and adapted to be extended rearwardly 25 over the head and having a longitudinal row of slots which are oblique to the length of said top member, adjacent ones of said slots inclining in opposite directions.

7. In a hair waving appliance, a front member 30 adapted to be applied to the upper and side portions of the face and having means for being fastened to the head, a top member attached at one end to said front member and adapted to be extended rearwardly over the head and having 35 a longitudinal row of slots oblique to its length and adjacent ones inclining in opposite directions, flexible hair engaging members adapted to be formed into U shape and having respectively T shaped engaging members insertable into and removable from said slots, whereby said flexible hair engaging members, are moved vertically when they are moved endwise, said hair engaging members being adapted to each have its end portions extend across said front member, and means 45 mounted on said front member for releasably fastening said end portions to said front member.

8. In a hair waving appliance, a front member adapted to be applied to the upper and side portions of the face, a flexible rod like member 50 adapted to embrace the rear side of the head and to have its end portions extend across said front member, a gripping member carried by said flexible member by which depending hair may be gripped against and wound upon said flexible 55 member when the latter is axially revolved, and means for releasably attaching said end portions to said front member when said flexible member with the hair wound thereon is made to embrace 60 the rear and sides of the head.

9. In a hair waving appliance, a front member adapted to be applied to the upper and side portions of the face, a hair engaging member having a flexible body and a longitudinal row of teeth, 65 and a spring clip fastened to said front member at the outer side thereof and having two arms between which said body is adapted for lateral insertion and which will releasably grip and hold said body from lateral movement and having 70 means for engaging one of said teeth and holding said hair engaging member from endwise movement.
